UNITED STATES PATENT OFFICE

CLAUDE W. KRESS, OF NEW YORK, N. Y.

DISPLAY CABINET

Application filed January 14, 1932. Serial No. 586,538.

My device relates to display cabinets and refers particularly to display cases having a false bottom of such construction that when moved vertically its respective elements will 5 retain a constant parallelism with the glass cover of the device.

Devices of this character are designed to display a plurality of commodities in an attractive and hygienic manner and should 10 be so constructed that they are capable of containing commodities of different sizes and shapes.

In order that contained commodities may 15 be presented in the most attractive manner it is essential that they be positioned as closely as possible to the under side of the glass cover, in order to avoid incident light reflections and to avoid shadows which would affect the individuality of the several pieces 20 of exhibited commodities.

As display cases should be capable of containing commodities of different heights, as nuts, candies and cookies, among alimentary products and a wide variety of fancy 25 and wearing articles, it is evident that they should be so constructed as to permit the articles to be positioned close to the glass cover irrespective of their heights, and my device accomplishes this desirable object in 30 a most efficient manner.

In my device I have a false bottom so arranged that commodities, irrespective of their size, placed thereon may be positioned in close 35 position to its glass cover.

The novelty and valuable properties of the display case of my invention will be evident upon a consideration of my specification and its accompanying drawing, in which similar parts are designated by similar numerals.

Figure 1 is a perspective view of one form 40 of the device of my invention.

Figure 2 is a section through the line 2-2 of Figure 1, with several positions of the false bottom indicated in designating lines.

Figure 3 is a section through the line 3-3 45 of Figure 1.

The particular form of the device of my invention illustrated in the accompanying drawing consists of a casing having the bottom 10, the sides 11 and 12, the ends 13 and

14 and the removable glass top member 15, 16 and 17. Extending longitudinally within the casing are two walls 18 and 19, and also extending longitudinally within the casing is a vertically movable false bottom 20, 21 55 and 22. The false bottom members 20 and 22 have openings 23, 23 to facilitate the removal of the false bottom from the casing and its vertical movement therein. The false bottom elements 20, 21 and 22 are in planes 60 parallel to the casing top members 15, 16 and 17 respectively, and hence a vertical movement of the false bottom will retain this parallelism. The walls 18 and 19 are in planes 65 parallel to the false bottom members 22 and 20 respectively.

A support having the sides 24, 24 and the top 25 extends longitudinally of the casing, and each guide 26, 26, fixedly attached to the top element 21 of the false bottom has a cut 70 out 27 in its lower portion allowing the false bottom to be guided during its vertical movement.

Each end portion of the element 25 is cut away to allow the insertion of a vertical 75 member 28, which is fixedly attached to an end member 13 or 14 of the casing and from which there is an inwardly extended threaded bolt 29.

Vertically movable between each member 28 and the top 25 of a guide is a member 30, having a vertical slot 31 through which a bolt 29 extends and a top member 32 having the same angular formation as the false bottom. The exposed faces of the members, 30, 30 have 85 a plurality of corresponding horizontal lines 33, 33.

A wing nut 34 and a washer 35 upon each threaded bolt 29 allow of the fastening of the members 30, 30 at any predetermined height. 90

In order to cover the space between the walls 18 and 19 and the lower ends of the false bottom members 20 and 22, I place a sheet of cardboard 20' and 22' thereon.

The operation of the device is as follows:— 95
The glass tops 15, 16 and 17, and the false bottom 20, 21, 22 are removed. The wing nuts 34, 34 are loosened and the supporting members 30, 30 are raised to the required height and fastened by means of the wing 100

nuts 34, 34, that the members 30, 30 are raised equally, being determined by the number of lines 33, 33 above the top 25. The false bottom is then placed within the casing, the commodities placed thereon and the glass top placed in position.

The broken lines and the dot-and-dash lines in Figure 2 represent graphically different raised positions of the false bottom, indicating several distances between the false bottom and the glass top.

It will thus be seen that by raising or lowering the false bottom 20, 21, 22, my device can be arranged to accommodate commodities of different heights, in each case positioning them in the desirable position of close proximity to the glass cover.

I do not limit myself to the particular size, shape, number, arrangement or material of parts as shown and described as these are given simply as a means for clearly describing the device of my invention.

What I claim is:—

1. In a display cabinet, in combination, a casing, a cover to said casing consisting of a plurality of glass elements angularly positioned with respect to the vertical and with respect to each other; a vertically movable false bottom within said casing consisting of a plurality of floor elements respectively parallel to the cover elements, whereby the spacing of said floor elements from the cover elements will be varied by said vertical movement, said floor elements being capable of retaining their parallelism with the cover elements during said vertical movement and means for retaining said false bottom in any desired vertical position.

2. In a display cabinet, in combination, a casing, a cover to said casing consisting of two oppositely inclined glass elements positioned at acute angles to the base of said casing in upwardly converging spaced relation and an intermediate glass element adjacent the spaced upper edges of said inclined elements and positioned parallel to said casing base; a vertically movable false bottom within said casing, said false bottom comprising three elements disposed relatively to each other similarly to said cover elements and which are respectively parallel to said cover elements, so that thus the spacing of such false bottom elements from the cover elements will be varied by said vertical movement, said false bottom elements being capable of retaining their respective parallelism with the cover elements during said vertical movement and means for retaining said false bottom in any desired vertical position.

3. In a display cabinet, in combination, a casing, a cover to said casing consisting of a plurality of glass elements angularly positioned with respect to the vertical and with respect to each other; a vertically movable false bottom within said casing consisting of

a plurality of floor elements respectively parallel to the cover elements; whereby the spacing of said floor elements from the cover elements will be varied by said vertical movement, said floor elements being capable of retaining their parallelism with the cover elements during said vertical movement, a vertically movable member capable of supporting said false bottom in a longitudinally level condition positioned at each end of said casing and means for retaining said vertically movable member at any predetermined height.

4. In a display cabinet, in combination, a casing, a cover to said casing consisting of two oppositely inclined glass elements positioned at acute angles to the base of said casing in upwardly converging spaced relation and an intermediate glass element adjacent the spaced upper edges of said inclined elements and positioned parallel to said casing base; a vertically movable false bottom within said casing, said false bottom comprising three elements disposed relatively to each other similarly to said cover elements and which are respectively parallel to said cover elements, so that thus the spacing of such false bottom elements from the cover elements will be varied by said vertical movement, said false bottom elements being capable of retaining their respective parallelism with the cover elements during said vertical movement, a vertically movable member capable of supporting said false bottom in a longitudinally level condition positioned at each end of said casing and means for retaining said vertically movable member at any predetermined height.

5. In a display cabinet, in combination, a casing, a cover to said casing consisting of a plurality of glass elements angularly positioned with respect to the vertical and with respect to each other; a vertically movable false bottom within said casing consisting of a plurality of floor elements respectively parallel to the cover element, whereby the spacing of said floor elements from the cover elements will be varied by said vertical movement, said floor elements being capable of retaining their parallelism with the cover elements during said vertical movement, a vertically movable member capable of supporting said false bottom in a longitudinally level condition positioned at each end of said casing, means for guiding said false bottom along straight lines during its vertical movement, and means for retaining said vertically movable member at any predetermined height.

6. In a display cabinet, in combination, a casing, a cover to said casing consisting of two oppositely inclined glass elements positioned at acute angles to the base of said casing in upwardly converging spaced relation and an intermediate glass element adjacent

the spaced upper edges of said inclined elements and positioned parallel to said casing base; a vertically movable false bottom within said casing, said false bottom comprising 5 three elements disposed relatively to each other similarly to said cover elements and which are respectively parallel to said cover elements, so that thus the spacing of such false bottom elements from the cover elements will be varied by said vertical movement, said false bottom elements being capable of retaining their respective parallelism with the cover element during said vertical movement, a vertically movable member 10 capable of supporting said false bottom in a longitudinally level condition positioned at each end of said casing, means for guiding said false bottom along straight lines during its vertical movement, and means for retaining 15 said vertically movable member at any predetermined height.

7. In a display cabinet, in combination, a casing having a transparent top closure including two downwardly and laterally outwardly inclined panel members, a vertically movable unitary false bottom within the casing including two downwardly and laterally outwardly inclined bottom elements respectively disposed in parallel spaced relation to 20 said inclined top closure panel members of the casing, guiding means cooperating between the casing and said false bottom for slidably guiding the latter relatively to the casing along rectilinear lines in its vertical 25 movement for thereby varying the spacing between while maintaining the parallelism of its said inclined elements and said inclined top closure panel members, and releasable sustaining means cooperating between the 30 casing and said false bottom for movably supporting the latter at different vertical positions thereof in the casing relatively to said top closure.

8. In a display cabinet, in combination, a casing having a transparent top closure comprising a horizontal longitudinally extending uppermost panel and two lateral panels respectively extending at an inclination downwardly and outwardly from the opposite 45 edges of the uppermost panel, a vertically movable unitary false bottom within the casing comprising a horizontal longitudinally extending uppermost bottom element spaced in parallel relation directly below said uppermost top closure panel and further comprising two lateral bottom elements respectively extending at an inclination downwardly and outwardly from the opposite edges of said 50 uppermost bottom element in respective spaced parallelism with said inclined panels of the top closure, guiding means within the casing below said false bottom for slidably guiding the latter relatively to the casing along rectilinear lines in its vertical 55 movement for thereby varying the spacing be-

tween while maintaining the parallelism of the respective false bottom elements to the respective opposed panels of the top closure, and releasable sustaining means within the casing below said false bottom for movably 70 supporting the latter in the casing at different vertical positions relatively to said top closure.

Signed at New York, in the county of New York and State of New York, this 8th day of January, 1981.
